[57] ABSTRACT

First controlled means are provided to impart a pivotal movement to a primary pivoted lever, to which a secondary pivoted lever is pivoted. Second controlled means are provided to impart to said secondary pivoted lever a pivoted movement relative to said primary pivoted lever. A processor roll is mounted on said secondary pivoted lever and engageable with the periphery of a coil of strip to be uncoiled. Said first and second controlled means are operable to hold said processor roll in engagement with the periphery of said coil as the latter decreases in diameter during the uncoiling of said strip.

MACHINE FOR WRAP FORMING METAL STRIP AS IT IS UNCOILED

This invention relates to a machine for wrap forming strip by a processor roll as the strip is uncoiled for further processing, which machine is preferably succeeded by a straightening machine.

When metal strip has been made from an ingot by hot rolling, the strip is coiled and in the form of a coil is stored and transported until it is processed further. These coils age in storage so that the uncoiling of the strip results in a formation of kinks, which can be eliminated only in part even by the application of high straightening pressures in the usually succeeding straightening machine and which adversely affect the processing of the strip. Pressure rolls consisting of so-called processor rolls have been engaged with the coiled strip as the same is uncoiled. These known arrangements, however, can be operated only with difficulty, particularly as the leading end of the strip is threaded through the arrangement and as the plant is started and give only inadequate results.

It is an object of the invention to prevent a formation of kinks in strip as it is uncoiled. The machine provided according to the invention and serving to wrap-form coiled strip by means of a processor roll as the strip is uncoiled for further processing is preferably succeeded by a straightening machine and is characterized in that the processor roll is mounted on a controllable secondary pivoted lever, which is mounted on a primary controlled pivoted lever to enable an adjustment of the processor roll to the coil as the uncoiling of the strip begins and as the uncoiling is continued with the diameter of the coil decreasing. This arrangement enables an adjustment of the processor roll in dependence on the diameter of the coil and the width and thickness of the strip so as to meet individual requirements.

Specifically, the primary pivoted lever is pivotally movable by means of a hydraulic or pneumatic actuator and carries a bending roller, which is disposed on the pay-off side of the coil of strip and carries a bending roll and the secondary pivoted lever provided with the processor roll, and the secondary pivoted lever is pivotally movable by a hydraulic or pneumatic actuator and pivoted to the primary pivoted lever at one end thereof, the processor roll is carried by said secondary pivoted lever at one end thereof and the actuator is connected to the secondary pivoted lever at the other end thereof.

A deflecting wedge is disposed between the processor roll and bending roll and is pivoted on the axis of the bending roll and pivotally movable by a wedge-operating lever, which is connected between the wedge and a further hydraulic or pneumatic actuator. In this way, the starting of the uncoiling, specifically, the threading of the leading end of the strip into the plant for further processing, is greatly facilitated.

Further details of the machine according to the invention will be described hereinafter with reference to the drawing, in which

FIG. 1 is a diagrammatic view showing in elevation the machine as the uncoiling of the strip from the reel begins.

FIG. 2 is a diagrammatic view showing in elevation the machine of FIG. 1 during the uncoiling of the strip from the reel, and

FIG. 3 is a diagrammatic view showing in elevation the machine of FIGS. 1 and 2 when the strip has been completely uncoiled from the reel.

As is apparent from the drawing, the uncoiling reel 1 carrying a coil of strip 2 is succeeded by a processor roll 3, which is mounted on a secondary pivoted lever 4. The latter is controlled by a hydraulic actuator 5. The secondary pivoted lever 4 is mounted on a primary pivoted lever 6, which is controlled by a hydraulic cylinder 7. The primary pivoted lever 6 carries at one end a bending roll 8, which is pivotally movable by the primary pivoted lever 6. A deflecting wedge 9 is pivoted on the axis of the bending roll and is pivotally movable by a hydraulic actuator 11 and a wedge-operating lever 10. As is apparent from FIG. 1 the wedge 9 guides the leading end of the strip 12 between the raised processor roll 3 and bending roll 8 as the uncoiling from the coil 2 begins. Thereafter, the wedge 9 is swung off the coil 2 by means of the primary rocker lever 6 and additionally by means of the actuator 11.

At a point preceding the processor roll 3, the coil of strip 2 is engaged by a pressure roll 13, which is raised to the position shown in FIG. 2 when the uncoiled strip 12 has been threaded between the feed rolls 14, which are preceded by an entering guide 15 and succeeded by a straightening machine 16 whereas the processor roll 3 and bending roll 8 have been pivotally moved to the position shown in FIG. 2. The pressure roll 13, the processor roll 3, the bending roll 8, the feed rolls 14, and the straightening rolls 16 are driven so that the total tensile load is distributed even in the case of relatively large coils of strip.

FIG. 1 shows the machine in position when the uncoiling of the strip begins. FIG. 2 shows the position as the uncoiling is continued. FIG. 3 shows the position assumed when the strip has been completely uncoiled.

A controlled pressure is applicable to the hydraulic or pneumatic actuator 5, which serves to impart a pivotal movement to the secondary pivoted lever 4 carrying the processor roll 3 so as to enable an adaptation to the properties of the strip as the same is threaded.

A controlled pressure is also applicable to the hydraulic or pneumatic actuator 7 for imparting a pivotal movement to the primary pivoted lever 6, to which the lever 4 is pivoted. The pressure applied to the actuator 7 can be controlled to change the contact pressure between the processor roll 3 and the coil of strip 2 in operative position in dependence on the dimensions and properties of the strip.

Further, the action of the hydraulic or pneumatic actuator 7 to impart a pivotal movement to the primary pivoted lever 6 and to the lever 4 pivoted thereto is adjustable even when a constant pressure is applied by the processor roll 3 to the decreasing coil of strip 2. This action of the actuator 7 can be adjusted by a control of the rate at which oil is supplied thereto if the actuator 7 is a hydraulic actuator.

What is claimed is:

1. A machine for wrap forming metal strip as it is uncoiled, which machine comprises
  - a primary pivoted lever,
  - first controlled means for imparting a pivotal movement to said primary pivoted lever,
  - a secondary primary lever pivoted to said primary pivoted lever,
  - second controlled means for imparting to said secondary pivoted lever a pivotal movement relative to said primary pivoted lever, and

a processor roll mounted on said secondary pivoted lever and engageable with the periphery of a coil of strip to be uncoiled,

said first and second controlled means being operable to hold said processor roll in engagement with the periphery of said coil as the latter decreases in diameter during the uncoiling of said strip.

2. A machine as set forth in claim 1, in which said first controlled means comprise a fluid actuator, said processor roll deflects said strip as it is uncoiled 10 from said coil, and

said primary pivoted lever carries a bending roll, which engages and deflect said strip when it has been deflected by said processor roll.

3. A machine as set forth in claim 2, in which said 15 first controlled means comprise a hydraulic actuator.

4. A machine as set forth in claim 2, in which said primary pivoted lever has a pivoted end and a free end,

said secondary pivoted lever has opposite first and 20 second ends and between said ends is pivoted to said primary pivoted lever at said free end thereof, said processor roll is mounted on said secondary pivoted lever at said first end thereof, and

said second controlled means comprise a fluid actuator, which is connected to said secondary pivoted lever at said second end thereof.

5. A machine as set forth in claim 4, in which said second controlled means comprise a hydraulic actuator.

6. A machine as set forth in claim 4, in which said second controlled means comprise a pneumatic actuator.

7. A machine as set forth in claim 4, in which said second controlled means are pressure-controlled.

8. A machine as set forth in claim 2, in which said first controlled means are pressure-controlled.

9. A machine as set forth in claim 8, in which said first control means are pressure-controlled and to maintain a constant contact pressure between said processor roll and said coil when the diameter thereof decreases as said strip is uncoiled.

10. A machine as set forth in claim 2, in which a deflecting wedge is disposed between said processing roll and said bending roll and guides said strip 45 to said bending roll when said strip has moved past said processing roll, and

third controlled means are connected to said deflecting wedge and operable to impart a pivotal movement thereto to and from a position in proximity to 50 said coil of strip.

11. A machine as set forth in claim 10, in which said wedge is carried by said primary pivoted lever and pivoted on the axis of said bending roll, and said third controlled means comprise a fluid actuator and a lever connecting said last-mentioned actuator to said wedge.

12. A machine as set forth in claim 1, which comprises a pressure roll arranged to engage the periphery of said coil of strip at a point preceding said processor roll in the direction of rotation of said coil as said strip is uncoiled, said pressure roll being disengageable from said coil.

13. A machine as set forth in claim 2, in which said processing roll and said bending roll are driven rolls.

14. In combination with an uncoiler adapted to carry a coil of metal strip and to uncoil strip from said coil, a machine for wrap forming said strip as it is uncoiled, which machine comprises a primary pivoted lever, first controlled means for imparting a pivotal movement to said primary pivoted lever, a secondary pivoted lever pivoted to said primary pivoted lever, second controlled means for imparting to said secondary pivoted lever a pivotal movement relative to said primary pivoted lever, and a processor roll mounted on said secondary pivoted lever and engageable with the periphery of said coil,

said first and second controlled means being operable to hold said processor roll in engagement with the periphery of said coil as the latter decreases in diameter during the uncoiling of said strip.

15. A plant for uncoiling and processing metal strip which is initially in the form of a coil, said plant comprising

an uncoiler adapted to carry said coil and to uncoil strip from said coil, processing means for processing said uncoiled strip, and a machine for wrap forming said strip between said uncoiler and said processing means and comprising a primary pivoted lever, first controlled means for imparting a pivotal movement to said primary pivoted lever, a secondary pivoted lever pivoted to said primary pivoted lever, second controlled means for imparting to said secondary pivoted lever a pivotal movement relative to said primary pivoted lever, and a processor roll mounted on said secondary pivoted lever and engageable with the periphery of said coil,

said first and second controlled means being operable to hold said processor roll in engagement with the periphery of said coil as the latter decreases in diameter during the uncoiling of the strip.

16. A plant as set forth in claim 15, in which said processing means comprise a straightening machine.

17. A plant as set forth in claim 15, which comprises feed rolls cooperating to feed said strip from said machine to said processing means.
